REFINING CUPOLA FURNACE

Peter Marx, Hennef-Sieg, Germany

Application October 19, 1931, Serial No. 569,759

5 Claims. (Cl. 266—11)

My invention relates to a cupola furnace, more particularly to a cupola furnace operated by electricity, oil, gas or the like fuel, such as, for instance, described in my Patent No. 1,911,379 of May 30, 1933, entitled Cupola furnace.

Up to the present it has been difficult economically and efficiently to effect the simultaneous melting and refining of the material to be treated, because compactly arranged furnaces of this type lacked the clear space necessary for developing a greatest possible thermal efficiency. Moreover, in these known furnaces the liquid material was not agitated; on account of the lack of agitation, it was hardly possible to separate injurious substances from said material.

Furthermore, the construction of these furnaces made difficult the rapid removal of the ash and other residue, so that they remained and affected the melting and refining process as well as the quality of the product.

In these furnaces the removable inner part, and it could not readily be cooled, resulting in a considerable increase in the costs of maintenance.

My invention overcomes these drawbacks, providing a refining cupola furnace for economical melting and refining in one continuous operation, heating by electric current, solid, powdered or fluid fuel.

One object of my invention is to provide an open combustion or heat space between the shaft or cupola furnace proper and the refining chamber for the purpose of facilitating abundant and intense development of heat at a point removed from the melting material, but in direct communication with the entire refining chamber, thereby providing efficiency in transmitting the heat to the melted material.

Another object of my invention relates to a predetermined propagation of the heat and to a circulation thereof—prior to entering the shaft—between refining chamber and shaft, thereby agitating the melting bath around the removable inner part of the furnace.

Still a further object of my invention is to shape the removable inner part of the furnace with a corrugated top, which extends into the cupola or shaft thus providing vertical openings which permit the passage of heat and of the melted material, but which do not allow the pieced charge to slide down from the shaft or cupola furnace.

Another object of my invention is to provide a double-wall construction of the removable inner part as well as to provide means for cooling it,

thereby increasing the life of the refractory covering.

In the accompanying drawings is shown an exemplary embodiment of my new furnace. There,

Fig. 1 is a longitudinal section

Fig. 2 is a cross section along the line 2—2 indicated in Fig. 1

Figs. 3 and 4 show longitudinal and cross sections of an electrically heated furnace.

Upon the heat chamber *a* enter the heat producing means, such as the burners *c* or the electrodes *b*; the refining chamber *h* receives the liquid, melted material. The shaft *j* accommodates the lumpy material to be melted; the removable, double-walled inner part *d* of the furnace, has a top *e* which is constructed at its circumference in a wave-like manner, thereby producing openings *g* extending vertically between said top and the wall *f* of the shaft and allowing heat to rise and melted material to pass down.

Conduits *M* and *N* introduce into and remove from the inside of inner part *d* a cooling fluid which is circulated as indicated by arrow heads. *l* denotes an inner member, and *m* constitutes the outer wall of a mantle which is cooled by said circulated fluids. The double-walled upper part *x* of the furnace is provided with a blast conducting spiral *y* located in the annular space *s*. The inner mantle *t* and the blast conducting spiral *y* of the upper part *x* of the furnace are replaceable; the outer wall *T* of the upper part of the furnace *x* may be insulated to prevent loss of heat. *R* is the smoke-stack.

The blast is admitted to spiral *y* through inlet *q* and the heated blast issues through outlet *r* into the intermediary tuyères *Z* and also, by way of ducts *Q*, into burners *c*.

In connection with furnaces operated by electric current it is possible to introduce the electrodes *b* in the heat chamber *a* from above as well as laterally (Fig. 3), an arc extending between the ends of said electrodes and the material.

By providing a particular combustion chamber around the shaft, material may be directly melted in the shaft by means of powdered or atomized fuel, and said material is subsequently refined in the refining chamber by subjecting it to a special heating, either by a fuel burnt in the heat chamber *a* or by an electric arc drawn from the electrodes *b* to the melted material in the melting chamber below; the heat gases ascend into the shaft.

According to my melting and refining process,

the furnace is charged with the pieced material to be melted and the heating means in the heat chamber are operated. As the pieced material melts down, new material is continuously fed from the platform, said material being supported by the top *e*, where it is melted by the ascending flames and/or by the heat supplied from tuyères *Z*. The liquid material flows through the vertical apertures *g*, in counter-flow to the ascending heat, into the refining chamber *h*, where it is mixed and refined in revolving around the removable inner part of the furnace *d*. The refined material is discharged through the outlet *k* as required. Prior to such discharge the slag which is formed during the melting and refining process, is skimmed off through outlets *A*.

My refining cupola furnace may be operated by the combination of different heating means, for instance of pulverized coke with atomized fuel, of coke with electric current, of coke with oil or gas. The furnace may also be used in other fields, for melting glass and enamel, for instance, in the ceramic industry.

What I claim is:

- 25 1. Refining cupola furnace for carrying out the process of melting and refining metals and the like comprising a cupola shaft, a refining chamber, heat chamber arranged between said shaft and chamber, said heat chamber being in direct communication with said shaft and refining chamber, a removable inner part of the furnace the top of which is shaped in a wave-like manner, thereby forming openings uniformly distributed on the periphery of said top, said openings being arranged vertically.
- 30 2. Refining cupola furnace for carrying out the process of simultaneously melting and refining metals and the like comprising a cupola shaft, a refining chamber, a heat chamber arranged between said shaft and chamber but outwardly off-

set therefrom, said heat chamber being disposed around and in direct communication with said shaft and refining chamber, and heating means revolving the atmosphere in said heat chamber, while heating it, said atmosphere being passed over the material in said chamber and through a contracted passage into said shaft.

5

3. Refining cupola furnace for carrying out the process of melting and refining metals and the like comprising a cupola shaft, a refining chamber, a heat chamber arranged between said shaft and chamber, said heat chamber being in direct communication with said shaft and refining chamber, and an inner part of the furnace having its top shaped in a wave-like manner, thereby forming openings uniformly distributed on the periphery of said top, said openings being arranged vertically.

10

4. Refining cupola furnace for carrying out the process of simultaneously melting and refining metals and the like comprising a cupola shaft, a refining chamber, a free heat chamber arranged between said shaft and chamber, said heat chamber being in direct communication with said shaft and refining chamber, a hollow inner part of the furnace invertedly extending centrally up therein, and means cooling the inside of said inner part.

15

5. Refining cupola furnace for carrying out the process of simultaneously melting and refining metals and the like comprising a cupola shaft, a refining chamber, a free heat chamber arranged between said shaft and chamber, said heat chamber being in direct communication with said shaft and refining chamber, a hollow inner part of the furnace invertedly extending centrally up therein, said part being constructed with double walls, and means cooling the inside of said inner part.
